(57) **CLAIM**

The ornamental design for a scraper spoon spatula, as shown and described.

DESCRIPTION

FIG. 1 is an isometric view of the scraper spoon spatula showing our new design.

FIG. 2 is a rear view thereof.

FIG. 3 is a rear detail view thereof showing contour lines.

FIG. 4 is bottom view thereof.

FIG. 5 is top view thereof.

FIG. 6 is a side view with the opposing side view being a mirror image thereof.

FIG. 7 is a front detail view thereof showing contour lines.

FIG. 8 is a section surface view taken along line 8-8 of FIG. 2.

FIG. 9 is a section surface view taken along line 9-9 of FIG. 2; and,

FIG. 10 front view thereof.

The broken lines shown in the drawings are for illustrative purposes only and form no part of the claimed design.
